SPOOL BOX OR THE LIKE

David Traum, 11 E. 26th St., Harrison, N.Y.

Filed Mar. 6, 1959, Ser. No. 54,865

Term of patent 14 years

(Cl. D3—19)

FIG. 1

FIG. 2

FIG. 3

Fig. 1 is a top plan view of a spool box, showing my new design;

Fig. 2 is a front elevational view thereof;

Fig. 3 is a side elevational view thereof, the side opposite thereto being substantially similar in appearance; and

Fig. 4 is a rear elevational view thereof.

I claim:

The ornamental design for a spool box or the like, substantially as shown and described.
